THE NORRIS PETERS CO., PHOTO-LITHO., WASHINGTON, D. C.

Inventor
Louis Kasan,
By his Attorney

Benjamin Roman.

UNITED STATES PATENT OFFICE.

LOUIS KASAN, OF NEW YORK, N. Y.

AWNING.

1,304,063.

Specification of Letters Patent. Patented May 20, 1919.

Application filed February 8, 1917. Serial No. 147,320.

To all whom it may concern:

Be it known that I, LOUIS KASAN, a citizen of the United States, and resident of the city of New York, in the county of 5 Kings and State of New York, have invented certain new and useful Improvements in Awnings, of which the following is a specification.

This invention relates to awnings, and its 10 principal object is to provide a simplified, inexpensive and improved awning that may be operated readily and conveniently and that will afford various conveniences to the user.

Another object is to provide an awning 15 that is laterally expansible to afford fitting thereof to windows or door-ways of various widths.

Another object is to provide an awning 20 having means for raising and lowering thereof by means of operating the sash of the window to which it is attached.

Other objects and advantages will hereinafter appear.

25 In the accompanying drawings,—

Figure 1 is a side elevation of the awning, showing it lowered.

Fig. 2 is a view similar to Fig. 1 but showing the awning raised.

30 Fig. 3 is a front elevation of the awning shown in Fig. 1.

Fig. 4 is a side elevation of the awning, showing its horizontal frame lowered into vertical position.

35 Fig. 5 is an end elevation, on an enlarged scale of the awning-roller and its casing.

Fig. 6 is a front elevation of the roller shown in Fig. 5.

40 Figs. 7 and 8 are a general view of the awning-roller and a cross section thereof respectively.

Figs. 9, 10, 11, and 12 show details of construction of the awning.

45 Figs. 13, 14, 15, 16 and 17 show details of construction of the awning-roller.

Fig. 18 shows a modification of the construction of the horizontal awning-frame.

Fig. 19 shows a modification of the roller casing as adapted to an arched window.

50 Fig. 20 shows a modification of the construction of the roller casing.

The awning proper comprises a roller 1 having thereto secured the end of a cloth 2 which passes around a cross-bar 3 and is 55 secured at its other end to a frame 4 that is horizontally disposed when in its normal operative state, Fig. 1. The roller 1,

Fig. 7, comprises a central tubular portion 5 with two cylindrical end portions 6 that are telescopically slidable therewithin toward and away from each other and are splined against rotation therewithin, whereby the length of the roller may be extended to any adjustment desired, depending upon the width of the window or doorway to 60 which the awning is attached and for which it is to be used. At one end of the roller 1 is secured a rope drum 7 and at each extremity of the roller is fixed a pin 8 having a head 9. Said roller is mounted 70 in operative position within a casing 10, Figs. 5, 6, comprising a hood 11, end-brackets 12, and a rear wall 13 which is secured to the wall 14 of the building by means of eye-bolts 15 passing through slots 75 16 thereof. To mount the roller 1 within the casing 10, its headed pins 9 are passed through the larger ends 17 of sinuous openings 18 in the end-brackets 12 and are seated into the opposite narrow ends 19 of these 80 openings. The casing 10 consists of two halves 20, 21, Fig. 19, the latter of which is telescopically slidable within the former, whereby the length of this casing may be adjusted to fit the adjusted length of the 85 roller 1. At each end of the casing-wall 13 is provided a hub 22 through which passes the extremity of a vertical guide bar 23 secured thereto by a set-screw 24. The bars 23 guide the cross bar 3, by means of 90 openings 3^a at its ends, Fig. 11, and they extend downwardly and pass through tubular bars 25, Fig. 9, which constitute their 95 lower portions and are secured to brackets 26 that are firmly fastened to the wall 14 by screws 27. The bars 23 are slidable within the fixed tubular bars 25 and are held in place therein, whereby the length of these guide-bars and consequently the height of the entire awning may be adjusted 100 to any extent desired to fit the height of any window. In order that the cross-bar 3 may be adjusted to any length desired to fit the adjustment of the roller 1 its central portion 28^a is made of two tubular parts 105 and telescopic with relation to each other. Similarly the end-bar 29 of frame 4 is made of two tubular parts and telescopic, whereby the horizontal frame 4 may be adjusted to any width desired to conform to 110 the adjusted length of the roller 1. The extremities of the side-bars 30 of the horizontal frame 4 are flattened in form and are provided with notches 31 that fit over

pointed projections 32 that form part of fittings 33 secured thereto by screws 33^a. Said fittings have angular extensions or ears 34 which pass over the guide rods 23 and serve as guides for the frame 4 while it is being lifted and lowered in the operation of the awning, and as hinges for the frame 4 when it is swung angularly from horizontal to vertical position. When the frame 4 is in normal horizontal position with the awning in lowered state, the end 35 of extension 34 abuts against the rear of the upper termination 36 of bracket 26, and the side 37 of the opening 38 of the fitting 33 rests against the opposite side of said socket. To adjust the width of the cloth 2 to conform to the desired width of the awning its sides are folded, as shown in Fig. 16, the ends 39 of the roller 1 being made narrower in diameter to provide more rolling space for these folded edges of the cloth. The ends of the cloth 2 are secured to the roller 1 and to the frame 4 by means of the thickened edges 40 thereof passing through grooves 41 that are widened at their bottoms, the end of the edge of the cloth being passed into the groove 41 of the frame through an enlarged opening 42. A rope 43 wound around the drum 7 and passing through a loop 44 serves to raise and lower the awning, and the end thereof may be tied to a knob 45, secured to bracket 26, for sustaining the awning in raised state.

It will be evident that in the installation of the awning the width thereof may be adjusted, to fit any width of window or door frame, by regulating the lengths of the roller 1 and bar 3, and adjusting the widths of frame 4 and the cloth 2, and the entire assembled awning may be secured in place against the wall 14 by merely threading thereinto the four screws 15, 27. To raise the awning merely requires pulling of the rope 43, whereupon the frame 4 is first swung about its pivot 38, so that its end 29 approaches the cross-bar 3, and then the frame and the cross bar are both elevated with the rolling of the cloth around the roller 1, until the entire window becomes uncovered, Fig. 2. Upon releasing of the rope 43 the reverse operation takes place and the awning is lowered to the position shown in Fig. 1.

Should it be desired to maintain the frame lowered and the frame 4 in normal horizontal position to prevent swinging thereof by the wind, a thumb-screw 46, passing through the fitting 33, may be tightened and its end caused to press forcibly against the fixed bracket 26 to secure said fitting and bracket together.

To dispose the frame 4 to the position shown in Fig. 4 to cause the cloth 2 to completely cover the window the screw 33^a may be untightened and the frame drawn away

from the pointed fitting-portion 32, whereupon the slot 47 in frame 4 may be utilized in conjunction with the screw 33^a to serve as a hinge about which the frame 4 may be swung and lowered to the downwardly vertical position shown. 70

According to the modified construction shown in Figs. 1, 5, the rope 43 passes around a pulley 48 mounted upon the bracket 12 and from there it passes inwardly 75 to the interior of the building and around another pulley 49 mounted upon the window-frame, wherefrom the rope extends to the lower window sash 50, whereby upon raising this window sash the awning is 80 caused to be lowered, while upon lowering of said sash the awning is raised.

In Figs. 13 and 17 is shown a modification of the awning roller, wherein the roller comprises two flat-metal bars 51 that are 85 embraced by a pair of sleeves 52, through which set-screws 53 are threaded to secure said bars in any adjusted position within the sleeves for regulating the length of the roller. The end of the cloth 2 infolds the 90 bars 51, and a set-screw 54 passing through a strap 55 that surrounds the cloth-end and a looped portion of each bar-end 56 serves to firmly bind these three parts together and also the same purpose as the pin 8 in 95 the roller 1. In conjunction with this construction of the awning roller the construction of the frame 4 is likewise modified, as shown in Fig. 18, wherein the frame comprises a pair of flat bars 57 surrounded by 100 a sleeve 58, and the cloth 2 passes through alined slots 59 of said bars and is held in place by the looped thickened extremity 60 thereof.

In the construction of the roller shown in 105 Fig. 7 lateral adjustment of the cloth is accomplished by means of passing its ends around pulleys 41^a and into grooves 41^b that are similar to the main groove 41. In the modification shown in Figs. 14, 15, and 16 110 110 the cloth 2 is secured to the awning-roller 1 by means of eyes 61 in the cloth passing over looped pins 62 fixed upon the roller. Fig. 19 shows the wall 13 of each casing-section extending upwardly at 63 and filling the 115 space between the casing and the arched side 64 of the window-frame 65.

In Fig. 20 the front part 11^a of the roller-casing is made independent of the upper wall 11^b of the hood and is adapted to slide 120 concentrically with the roller, in the direction of the arrow, within radial guiding slots 12^a provided in the bracket 12, whereby the front wall 11^a may be swung backward and rendered out of sight, during periods of dry fair weather, to give better 125 appearance to the awning structure.

It will be evident that in assembling the awning cloth during installation of the awning to permit adjustment of the width 130

thereof the cloth may be folded several times at the central portion thereof in a manner similar to the folding of its side portions, as shown in Fig. 16.

5 Variations may be resorted to within the scope of the invention, and portions of the improvements may be used without others.

Having thus described my invention, I claim:—

10 1. In an interchangeable awning for installation upon windows of various sizes, means for regulating the lateral extent thereof in the installation including a single cloth having its lateral extent regulated by 15 means of folding each of its side edges to conform to the required width for fitting it to the required adjusted width of the awning.

2. An awning including the combination 20 of a roller for winding cloth therearound having means for regulating the length thereof and its ends of lesser diameter than its intermediate portion, and a cloth for said roller adapted to have the width thereof 25 regulated to conform with the regulated length of said roller by means of folding its side-edges and having said edges disposed around the portions of said roller which are of lesser diameter.

30 3. An awning having a fixed frame including a pair of vertical rods, a laterally adjustable swingable frame, a roller for winding cloth therearound having means for regulating the length thereof for fitting 35 it to the adjusted width of said swingable frame, cloth for said roller having the width thereof regulated to conform to the adjusted width of said swingable frame, and a cross bar for bending said cloth thereat having 40 means for regulating the length thereof to the adjusted width of said cloth being slideable vertically along said vertical rods.

45 4. An awning having the combination of a cloth, a swingable frame therefor, a stationary frame, fittings for supporting said former frame being hinged to said stationary frame, means to adjust the elevation of said hinged fittings along said stationary frame, and means to secure said hinged 50 fittings against swinging to said stationary frame in any adjusted position.

55 5. An awning having the combination of a cloth, a swingable frame therefor, a stationary frame, fittings for supporting said former frame being hinged to said stationary frame, said fittings being adjustable vertically and securable along said stationary frame in any position, and means to render 60 said swingable frame hingeable about said fittings when they are in secured state to permit disposition of said swingable frame in vertically downward position.

6. An awning having the combination of

a cloth, a swingable frame therefor, a stationary frame, fittings for supporting said former frame being hinged to said stationary frame, said fittings being adjustable vertically and securable along said stationary frame in any position, means to render said swingable frame hingeable about said fittings when they are in secured state to permit disposition of said swingable frame in vertically downward position, and means to secure said swingable frame to its fittings in normal horizontal position.

7. An awning having an adjustable cloth, an adjustable roller for winding said cloth therearound, and a casing surrounding said roller being longitudinally adjustable, and the front part of said casing being curved 80 and independent and adapted to slide in the direction of its curvature forwardly and rearwardly to cover and uncover said roller.

8. An interchangeable awning for installation upon windows of various sizes having 85 the combination of a laterally adjustable roller, a laterally adjustable cloth, said cloth having a thickened end, said roller having a slot extending therealong in a longitudinal direction, said slot being wider at its 90 bottom than at the periphery of the roller, and said cloth being secured to said roller by having its thickened end passed longitudinally through said slot.

9. In an interchangeable awning for installation upon windows of various widths, means for regulating the lateral extent of the awning including the combination of a longitudinally adjustable roller, a laterally adjustable frame, a single cloth being secured at its ends to said frame and said roller, and said cloth having its lateral extent regulated in the installation by means of folding each of its side edges to conform to the width of said frame and the length of 105 said roller for fitting it to the required adjusted width of the awning.

10. An awning having the combination of a stationary frame, a laterally adjustable swingable frame thereon, a laterally adjustable cloth for said frame, an adjustable roller for said cloth, rope actuated mechanism for operating said roller, a casing surrounding said roller being longitudinally adjustable, the rear part of said casing having receiving means for said stationary frame, and the end of said casing having guiding means for the rope of said mechanism.

Signed at the city of New York, in the 120 county of New York, and State of New York, this 2nd day of February, A. D. 1917.

LOUIS KASAN.
